PRESSER-FOOT FOR SEWING MACHINES

Frederic M. Card, Bridgeport, Conn., assignor to
The Singer Manufacturing Company, Elizabeth, N. J., a corporation of New Jersey

Application March 27, 1937, Serial No. 133,374

8 Claims. (Cl. 112—235)

This invention relates to improvements in presser-feet of sewing machines and more particularly in the compensating type of presser-feet in which an equalizing device is interposed between relatively movable work-engaging foot-plates of the presser-foot to maintain uniformity of pressure upon different thicknesses of work.

The present invention has for its object to increase the responsiveness of the work-engaging members of a compensating presser-foot to variations in the thickness of the material engaged thereby, and to this end the component parts of the presser-foot are constructed and arranged to minimize cramping action in the response of said parts to differences in the thickness of the work. The invention will be understood by reference to the accompanying drawing, which illustrates a preferred embodiment of the invention and in which:—

20 Fig. 1 represents a perspective view, partly in section, of the presser-foot. Fig. 2 is a side elevation, partly in section, of the same. Fig. 3 represents a section of the presser-foot substantially on the line 3—3 of Fig. 2. Fig. 4 represents a section of the presser-foot substantially on the line 4—4 of Fig. 2.

Referring to the drawing, the presser-foot has a body comprising a substantially rectangular block 1 preferably integral with the lower end 30 of a flat shank 2 adapted to be attached to any usual or suitable presser-bar of a sewing machine. (Not shown.)

The shank-block 2 is provided lengthwise thereof with a pair of substantially parallel and vertically disposed guide-slots 3 and 4, which are preferably cut into said block from the under side thereof so as to be open at the bottom of the block. Slidably disposed in the respective guide-slots are relatively movable and preferably flat-sided leg-members 5, each pivotally attached to the block 1 at the rearward end thereof by means of a transverse and horizontally-disposed fulcrum-pin 6. The fulcrum-pin 6 is secured to said block by a set-screw 7 and provides a coaxial 45 pivotal support for said leg-members.

At their rearward ends, the leg-members 5 are each shouldered to provide an upwardly extending stop-lug 8 adapted to engage the rear face of the block 1, thereby to limit downward movement of the forward ends of said leg-members.

The leg-members 5 extend forwardly beyond the block 1 and have reduced free ends which are transversely apertured to receive pins 9 pivotally supporting the upstanding spaced lugs 10 55 and 11 of adjacent foot-plates 12 and 13. The

foot-plate 12 is provided with a needle-clearance recess 14 which is preferably open at the inner side edge 15 of said foot-plate, said side-edge being partly cut away in the upturned toe 16 of the foot-plate 12 to facilitate directing work 5 against the inner side edge 17 of the foot-plate 13. Obviously, the toe 18 of the foot-plate 13 may also be cut away in its inner side edge 17 to facilitate the use of the inner side edge 15 of the foot-plate 12 as an edge-guide for the work. 10

Threaded into the front face of the block 1, between the leg-members 5, is a shouldered screw 19 upon which is fulcrumed a two-armed equalizing-lever 20 for rocking movement about a horizontal axis transverse to the fulcrum-axis of 15 the leg-members 5. The lever 20 is disposed in front of the block 1 and is cut away so that the two arms thereof present flattened lower faces overlying and in direct engagement with the upper edges of the leg-members 5. In order to 20 insure operative engagement of said equalizing-lever 20 and leg-members 5, the upper edges of said leg-members are recessed rearwardly of the leg-member fulcrum-pin 6 to receive coil-springs 21 reacting against the upper walls 22 of the slots 25 3 and 4, thereby yieldingly holding the forward ends of the leg-members 5 in engagement with the equalizing-lever 20. The slot walls 22 also function as stops limiting upward movement of the forward ends of the leg-members 5. 30

It will be understood from the foregoing description that within their range of relative movement, the foot-plates 12 and 13 are free to adapt themselves to different thicknesses of work respectively engaged thereby and to ride cross-seams, while maintaining a substantially uniform pressure upon the work. By arranging the component parts of the presser-foot so that the equalizing-lever 20 is in direct engagement with the pivotal leg-members 5, and by eliminating 40 the vertically sliding guide-plungers heretofore commonly employed in compensating presser-feet, cramping of the parts is substantially eliminated and the foot-plates are free to relatively respond to variations in the thickness of the 45 work. 35

Having thus set forth the nature of the invention, what I claim herein is:—

1. A presser-foot for sewing machines, comprising a body, a pair of leg-members coaxially pivoted to said body, foot-plates pivotally attached to and carried by the respective leg-members, and an equalizing-lever fulcrumed between its ends upon said body in position for direct engagement with said leg-members. 55

2. A presser-foot for sewing machines, comprising a body, a pair of leg-members coaxially pivoted to said body, foot-plates pivotally attached to and carried by the respective leg-members, an equalizing-lever fulcrumed between its ends upon said body, and means yieldingly holding said leg-members in engagement with said lever.
3. A presser-foot for sewing machines, comprising a body having a shank and a block integral with said shank, a pair of forwardly extending leg-members pivotally attached to said block at the rearward end thereof for relative movement of said leg-members about a substantially horizontal axis, foot-plates carried by the forward ends of the respective leg-members, an equalizing-lever in direct engagement with said leg-members and fulcrumed between its ends upon said block for rocking movements about a substantially horizontal axis transverse to the pivotal axis of said leg-members, and means for holding said leg-members in engagement with said equalizing-lever.
4. A presser-foot for sewing machines, comprising a supporting shank, a block carried by said shank, a pair of forwardly extending leg-members pivotally attached to said block at the rearward end thereof for relative movement of said leg-members about a substantially horizontal axis, foot-plates pivotally attached to and carried by the forward ends of the respective leg-members, an equalizing-lever in operative engagement with said leg-members and fulcrumed between its ends upon the front end of said block for rocking movements about a substantially horizontal axis transverse to the pivotal axis of said leg-members, and means limiting downward movement of the forward ends of said leg-members.
5. A presser-foot for sewing machines, comprising a shank-body formed with substantially parallel guide-slots, leg-members slidably disposed in said guide-slots and pivotally attached to said body at the rearward end thereof, foot-plates carried by the forward ends of the respective leg-members, an equalizing-lever fulcrumed between its ends upon said body in overlying en-

gagement with said leg-members, and yielding means for holding said leg-members in engagement with said equalizing-lever.

6. A presser-foot for sewing machines, comprising a shank-body formed with substantially parallel guide-slots, leg-members slidably disposed in said guide-slots to extend forwardly from said body and having a coaxial pivotal support upon said body, foot-plates pivotally carried by the respective leg-members, an equalizing-lever fulcrumed between its ends upon said body and having its arms in operative engagement with said leg-members, springs housed within said body and bearing upon said leg-members to hold the forward portions of said leg-members in engagement with said equalizing-lever, and means limiting movements of said leg-members in opposite directions.

7. A presser-foot for sewing machines, comprising a shank-body formed lengthwise thereof with substantially vertical and downwardly open guide-slots, leg-members slidably disposed in said guide-slots to extend forwardly from said body and having a coaxial pivotal support at the rearward end of said body, stops carried by the respective leg-members for engagement with said body and thereby to limit downward movement of the forward ends of the respective leg-members, an equalizing-lever fulcrumed between its ends upon the front end of said body and having its arms in overlying engagement with said leg-members, and springs bearing upon said leg-members to hold said leg-members in engagement with said equalizing lever.

8. A presser-foot for sewing machines, comprising a shank-body, a pair of forwardly extending leg-members pivotally attached to said body at the rearward end thereof for relative movement of said leg-members about a substantially horizontal axis, foot-plates pivotally carried by the forward ends of said leg-members, and a leg-member equalizing-lever disposed forwardly of the front face of said shank-body and fulcrumed between its ends upon said body for rocking movements about a substantially horizontal axis transverse to the pivotal axis of said leg-members.
